UNITED STATES PATENT OFFICE

CHARLES H. DAVIS AND HENRY W. LUECK, OF PARK RIDGE, ILLINOIS, ASSIGNEES TO
MATHIAS KLEIN AND SONS, OF CHICAGO, ILLINOIS, A CORPORATION OF ILLINOIS

SNAP

Application filed May 15, 1929. Serial No. 363,140.

Our invention relates to snaps, and more particularly to means for preventing a snap fastener from becoming detached or opened accidentally.

5 Our invention is particularly applicable to the snaps which are used in connection with the safety straps and belts used by linemen in working on electric lines.

It is the principal purpose of this invention 10 to provide a device of this character wherein the loop into which the snap fastens cannot be removed from the snap except by manipulation of the loop into a certain definite position relative to the snap.

15 It is also a purpose of this invention to provide means in connection with the snap which will prevent the keeper thereof from being accidentally misplaced due to the snap scraping against or catching on projections 20 of any sort.

Other more detailed objects and advantages of the invention will appear as the description proceeds in connection with the accompanying drawings. It is to be understood, however, 25 that we do not intend to limit ourselves to the exact details shown and described, but that we intend to avail ourselves of all such modifications as would occur to one skilled in this art and as fall within the scope of the 30 claims.

In the drawings,—

Fig. 1 is a top view of a lineman's belt and safety strap employing my invention;

Fig. 2 is an enlarged view of the snap and 35 ring;

Fig. 3 is a plan view of the snap and ring; and

Fig. 4 is a side view of a slightly modified 40 form of the invention.

Referring now in detail to the drawing, a lineman's belt is made up usually of the heavy holding strap 5 and a surrounding strap 6 which extends around the heavy holding strap and may or may not be fastened thereto per-

45 manently, this strap 6 being adapted to pass around the waist of the user and be buckled together at 7. The hold-back strap 5 terminates on opposite sides of the buckle 7, as shown at 8 and 9, and is secured, in the 50 present instance, by means of a rivet 10 to the

55 snap 11. This is somewhat different from past standard practice because it has been the practice to place the ring 12 upon the hold-back strap 5, and place the snaps 11 upon the safety strap 13. We find it advantageous, however, as will be more fully pointed out hereinafter, to place the snap itself upon the belt or hold-back strap, and place the ring 55 upon the safety strap.

The snap 11, preferably made of a very 60 strong, tough metal, has the free end portion thereof extended well back, as shown at 14, so as to cover the keeper 15, this keeper being pivoted, in Figs. 1 to 3, at 16 to an upstanding projection on the snap. A spring 17 is 65 suitably held between the keeper and the lower portion of the snap to yieldingly force the keeper upwardly against the top portion 14 of the snap. The keeper is, of course, provided with the depending flanges, as indicated 70 at 18, to prevent the spring 17 from being displaced by foreign elements getting in contact therewith, and these flanges also serve as a guide to prevent lateral displacement of the 75 keeper.

As a further means of preventing lateral displacement of the keeper, the upstanding projections, such as indicated in dotted lines at 19, are provided to engage the opposite 80 sides of the top 14 of the snap, this top being cut away to permit of this engagement without having the keeper extend laterally beyond the width of the top portion. The nose of the keeper is turned down and then slightly 85 up again, as shown at 20, to provide a more or less V-shaped notch 21 as the only place in which the ring 12 may engage to force the keeper into open position. The upturning of the free end of the nose makes it less likely 90 that anything but the right portion of the ring will get beneath it.

This ring 12, as shown, is provided along 95 one interior side edge with a pointed portion 22 which is sufficiently V-shaped to engage in the recess 21 to force the keeper down and permit removal of the ring from the snap. This is particularly clear in Fig. 4, wherein the ring is shown in the position in which it must be placed to engage the keeper and remove it from locking position.

It will be noted from an inspection of Figs. 2 and 4 that it is necessary to substantially reverse the ring from its normal pulling position and bring the safety strap 13 back toward the point of the top portion 14 of the snap before the ring can engage in the recess 21 to force the keeper into open position. As this position is one which it is practically impossible to attain with any force thereon, it is readily apparent that accidental displacement of the ring from the snap cannot take place in applicants' device due to the ring forcing the snap keeper into open position. Moreover, the top portion 14 extending over the keeper 15 effectively prevents sharp projections or corners from pushing this keeper down, and thus releasing the ring from the snap. The snap, being pivoted upon the belt may, of course, follow the ring in any position the snap forces it, so that it is necessary to properly position them by manual operation before they can be separated.

We find another advantage in having the ring upon the safety strap, which lies in the fact that a strap with rings in the ends is much less apt to be used for some unauthorized purpose, such as a tow line, than one would be which had snaps in the ends. This prevents the linemen from using their safety straps where they would be subjected to excessive strains which would weaken them beyond the point of safety.

In the device shown in Fig. 4, the only distinction between its operation and that shown in Figs. 1 to 3 lies in the fact that the keeper 15' is secured at 16' to the nose 14' of the top portion of the snap, the spring 17' being also placed between the keeper and the top portion 14' of the snap. The construction otherwise is identical, and need not be further described herein.

From the above description, it is thought that the construction and advantages of this device will be clear to those skilled in this art, and having thus described our invention, what we claim as new and desire to secure by Letters Patent is:

1. In a device of the character described, a snap having a spring-pressed keeper, a ring therein and cooperating means on said ring and snap whereby to permit depression of said keeper by the ring to remove said ring only when the ring is in one definite position relative to said snap.

2. In a device of the character described, a snap having a spring-pressed keeper, a ring therein and cooperating means on said ring and snap whereby to permit depression of said keeper by the ring to remove said ring only when the ring is in one definite position relative to said snap, said means including a wedge-shaped inner edge portion at one side of said ring the outer surface of said ring being blunt and rounded.

3. In a device of the character described, a snap having a spring-pressed keeper, a ring therein and cooperating means on said ring and snap whereby to permit depression of said keeper by the ring to remove said ring only when the ring is in one definite position relative to said snap, said means including a wedge-shaped inner edge portion at one side of said ring, and means on said snap and keeper forming a wedge-shaped recess for receiving said portion, said wedge-shaped recess being proportioned to prevent all portions of said ring except said wedge-shaped portion to enter sufficiently to open the keeper. 70 75

4. A snap comprising a body portion having a hooked end, a keeper pivoted to said body portion, resilient means resisting depression of said keeper and said body portion being extended on the side opposite said resilient means to cover said keeper. 80 85

5. A snap comprising a body portion having a hooked end, a keeper pivoted to said body portion, resilient means resisting depression of said keeper and said body portion being extended on the side opposite said resilient means to cover said keeper, said keeper and snap having cooperating portions for permitting an article held therein to depress said keeper only when said article is pulled in one direction relative to said snap. 90 95

6. A snap comprising a body portion having a hooked end, a keeper pivoted to said body portion, resilient means resisting depression of said keeper and said body portion being extended on the side opposite said resilient means to cover said keeper, said keeper and snap having cooperating portions for permitting an article held therein to depress said keeper only when said article is pulled in one direction relative to said snap, said portions forming a tapering recess in the inner surface defined by said snap and keeper. 100 105

7. In a device of the character described, a snap having means for securing the same to a belt or the like and having a spring-pressed keeper, a ring insertible into said snap by depression of said keeper and locking means preventing depression of said keeper by said ring except when said ring is extended toward the secured end of said snap and force applied thereto in the direction in which the ring is extended. 110 115

8. In a device of the character described, a belt snap pivoted to said belt having a depressible keeper, a strap having a ring engageable in said snap and means on said ring and snap whereby said ring can depress the snap keeper only when the strap and ring are doubled back toward the pivoted end of the snap. 120 125

9. In a device of the character described, a belt snap pivoted to said belt having a depressible keeper, a strap having a ring engageable in said snap and means on said ring and snap whereby said ring can depress the 130

snap keeper only when the strap and ring are doubled back toward the pivoted end of the snap, said means including a tapered inner wall portion on said ring opposite where it is secured to the strap.

- 5 10. In a device of the character described, a belt snap pivoted to said belt having a depressible keeper, a strap having a ring engageable in said snap and means on said ring and snap whereby said ring can depress the snap keeper only when the strap and ring are doubled back toward the pivoted end of the snap, said means including a tapered inner wall portion on said ring opposite where it is secured to the strap and a projection on the keeper forming a tapered recess with the inner wall of said snap.
- 10 15

In witness whereof, we hereunto subscribe our names this first day of May A. D., 1929.
